UNITED STATES PATENT OFFICE.

WILLIAM H. PARRY, OF KENOSHA, WISCONSIN, ASSIGNOR TO THE SIMMONS MANUFACTURING COMPANY, OF KENOSHA, WISCONSIN, A CORPORATION OF WISCONSIN.

ASSEMBLING-RIG.

1,148,713.

Specification of Letters Patent.

Patented Aug. 3, 1915.

Application filed February 9, 1914. Serial No. 817,495.

To all whom it may concern:

Be it known that I, WILLIAM H. PARRY, a citizen of the United States, residing in the city of Kenosha, county of Kenosha, and State of Wisconsin, have invented certain new and useful Improvements in Assembling-Rigs, of which the following is a specification.

My invention relates to improvements in assembling rigs, and refers more particularly to apparatus used for assembling wooden panels by pneumatic pressure.

Among the salient objects of the present invention are to provide an apparatus for assembling together, by pneumatic pressure applied in two directions, the various constituent parts of wooden panel structures; to provide an apparatus of the class described which may be operated by practically unskilled help, which contains no delicate parts to get out of adjustment, which is extremely simple to operate, and in which the assembling pressure is applied in both directions by the manipulation of a single controlling lever; to provide an apparatus of the class described which may be adjusted to accommodate various sizes of panels or other structures to be assembled by changing minor mechanical details of the device; to provide an apparatus which will be at all times positive and reliable in its operation, and which will always produce a finished product uniform in size and fit; to provide an apparatus of the class described which may be very easily maintained in effective operation, and which will be simple and economical of construction; and in general to provide an improved apparatus of the character referred to.

My invention consists in the matters hereinafter described, and more particularly pointed out in the accompanying drawings, in which,—

Figure 1 represents a plan view of my apparatus as constructed for assembling the backs of wooden folding chairs, the apparatus being shown with the pistons withdrawn to permit the insertion of the parts; Fig. 2 is another plan view of the apparatus shown in Fig. 1, showing the chair-back in assembled relation after it has been operated upon by the plungers; Fig. 3 is a side elevation taken from the right of Fig. 1; Fig. 4 is a view in section, taken from the right 55 of Fig. 2, along a section line correspond-

ing to the axis of the end rail assembling cylinder; Fig. 5 is an end elevation of Fig. 2; Fig. 6 is a longitudinal section taken through the axis of the controlling valve; Fig. 7 is a cross section of Fig. 6, taken 60 along the line 7 looking in the direction of the arrow; Fig. 8 is a cross section of Fig. 6, taken along the line 8 looking in the direction of the arrow; and Fig. 9 is a fragmentary sectional view taken along the line 65 9 of Fig. 4.

Referring to the drawings, 1 represents as a whole the cast-iron base, supported upon the legs 2, which are indicated in Figs. 3 and 5, but are broken off in order to reduce 70 the size of the drawing. Upon two extensions 3 and 4 of the base are bolted the two pressure cylinders 5 and 6. These cylinders contain pistons 7, which are connected to piston rods 8 sliding within stuffing boxes 9 75 in the front head 10 of each cylinder. Each cylinder is constructed from a tube, the back end of which is closed by a stationary head 11, the piston being inserted by removing the front head 10, which has a 80 flange provided with screw threads engaging the exterior of the end of the cylinder. To the front end of the piston rod of the cylinder 5 is secured a plunger block 12, the lower portion or foot 13 of which slides 85 freely in a slot formed in the top of the base casting 1. This is clearly shown in Fig. 9. The piston rod of the other cylinder 6 is fitted with a similar plunger block 14, which is also arranged to slide in a similar 90 slot in the upper portion of the base casting 1. The plunger 12 is formed with a pair of projecting wings or arms 15, 15, which are of equal size and dressed off to furnish a pair of pushing surfaces 16 in alinement 95 and at right angles to the axis of the cylinder 5. The axis of the cylinder 6 is arranged in this instance at right angles to the axis of the cylinder 5, and its plunger block 14 is also provided with a pair of similar 100 wings or arms provided with corresponding pushing surfaces 16', also at right angles to the axis of the cylinder.

Upon the surface of the base casting 1 are mounted a pair of strips 17 for the purpose of bringing the slats of the panel to the height necessary for their entering slots or kerfs in the end members of the chair-back. The small angle pieces 18, which are bolted to the depressed surface of the table, 110

are for the purpose of furnishing a pair of stops against which to place the initial one of a number of slats in order to locate them in proper position for assembling. The up-
5 standing lugs 19 receive the thrust due to the pressure of the cylinder 6 transmitted to the chair members while they are being assembled. The upwardly projecting rib 20 of the bed, Figs. 1, 2 and 4 in a similar
10 manner receives the thrust pressure of the cylinder 5 transmitted to the slats and end rails while they are being assembled together.

The valve control will now be described.
15 Each cylinder is operated by compressed air of suitable pressure admitted to the front or to the back thereof, depending upon which way the piston is to be operated. The actual assembling of the chair
20 members is effected by admitting air to the backs of the cylinders, and thus pushing the plungers forward. During the time that the air under pressure is being supplied to the rear of either one of the cylinders, the
25 front end of that particular cylinder is open to the atmosphere, and thus exhausting. In order to effect withdrawal of the plunger previous to another cycle of assembling operations, air under pressure is admitted to the front, while the back end is allowed to exhaust freely.

Secured to the lower part of the base casting 1, upon a suitable bracket 21, is mounted a cylindrical casting 22, which, as seen in Fig. 6, is made in two sections, threaded together so as to permit the insertion of the rotary valve 23. The latter consists of a flattened cylindrical head portion provided with a hollow sleeve which extends through a cylindrical hole in the casting 22 and projects therefrom far enough to permit the attachment of the control handle 24. The handle 24 is suitably keyed to the sleeve of the valve so that it may positively oscillate the latter. The head portion of the valve 23 is of such size as to give ample clearance between it and the cylindrical chamber 25 in the casting 22, within which the valve is located.
35 One end of the chamber 25 forms a valve seat, against which the valve operates and is pressed by the action of the air under compression in the chamber 25. The air supply is conducted to the valve chamber through the threaded opening 26 by means of a pipe line 27 which communicates with the air main through the shut-off valve 28. In the rotary valve-head are drilled three cylindrical openings 29, 30 and 31, which pass from the front to the rear of the valve-head, as shown in Fig. 6, their position in the head being clearly shown in Fig. 8. These ports are thus always in direct communication with the compressed-air supply, and admit pressure to the cylinder ports

when the valve is oscillated into the right position. The valve-head is also apertured in three places, as illustrated in Fig. 8 at 32, 33 and 34, each opening, as shown in Fig. 6, consisting of a radial portion which communicates with the longitudinal hole in the sleeve of the valve, and a short longitudinal portion which connects the radial portion with the operating face of the valve. The ports just described are for the purpose of exhausting the air from the cylinders, the spent air passing out through the longitudinal hole in the valve-sleeve. The main body portion of the stationary-valve-chamber casting is provided with four right-angled valve ports 35, 36, 37 and 38 leading from the exterior of the valve cylinder to the working valve face, the position of each port in the face being shown in Fig. 7. The valve port 35 communicates by means of a pipe 39 with the back end of the cylinder 5, the front end of which is connected to the port 38 by a pipe 40. The port 36 is connected to the back end of the cylinder 6 by a pipe 41, and the front end of the cylinder to the port 37 by a pipe 42.

The valve handle 24 has three positions. In the position shown in full lines, which I designate *a*, the ports occupy the relation shown in the various sectional views of the valve mechanism. In this position, the port 30 is in register with the port 38, and thus admits air to the front of the cylinder 5, the back of the latter being placed in communication with the atmosphere by the right-angled exhaust-port 33 now in register with the port 35. In a similar manner, the front end of the cylinder 6 is supplied with air under pressure through the port 31, which registers with the port 37; the back-end exhaust being effected by the position of the port 34 now in register with the port 36. It will thus be clear that in the position *a* of the handle both cylinders will be under pressure at their front ends and exhausting at the back, and the plunger blocks withdrawn.

When the handle is moved to the position *b*, shown dotted in Fig. 3, the port 35 leading to the back end of the cylinder 5, while the port 32 will at the same time be placed in register with the port 38, which communicates with the front end of the same cylinder. Thus air under pressure will enter the back of the cylinder and force the piston and plunger block outwardly, while the front end of the cylinder exhausts freely through the hollow valve-stem. While this is going on, the ports 36 and 37 of the other cylinder 6 have been closed by the oscillation of the valve, and thus nothing happens to the piston of that cylinder. If the handle were left in the position *b* for a considerable length of time, obviously the

difference in pressure between the front and back of the cylinder 6 would gradually equalize itself by leakage, but no movement would occur.

If the valve now be oscillated so that the handle occupies the position shown at *c* in dotted lines in Fig. 3, the valve-port 29 comes into alignment with the end of the port 36, and thus admits compressed air to the back of the cylinder 6. In this position the port 32 is in register with the port 37, which conveys the exhaust from the front end of the cylinder. The effect is thus to push forward the piston and plunger block of the cylinder 6. While this condition prevails, the ports 35 and 38 are completely sealed by the movement of the valve, and no change is made in the air pressure on either side of the piston, which thus remains in its previous position. It should here be noted that the arc of movement of the handle 24 is limited to the top quadrant of the circle, and to move the handle from the position *c* to the position *b*, or vice versa, it must pass through the middle position *a*. As previously described, when in this *a* position, both pistons are withdrawn to their respective back ends. It is thus obvious that there will never be at one time more than one of the pistons in advanced operating position. When in the position *b*, the cylinder 5 will be operating, while the cylinder 6 is holding back its plunger; and when in the position *c*, the cylinder 6 will be operating, while the cylinder 5 is holding back its piston and plunger.

When actually using the apparatus to assemble the panel of a chair-back, I first of all place the top end member or rail 44 upon the slightly raised portion 45 of the base casting and against the side of the rib 20. The lower end member or rail 46 is then placed upon the raised portion 47 and against the pushing surfaces 16 of the plunger 12. The side leg or stile 48 is then laid edgewise in the corner formed by the lugs 19, and the little bracket 49 bolted to the top of the base casting. The other side leg or stile 50 is then also laid edgewise in the corner formed by the locating bracket 51 and the two pushing surfaces 16', the bracket 51 being of such height as to engage the lower edge of the member or stile 50, while not interfering with the advance of the plunger block 14. The slats 52 are then laid flat upon the strips 17 and pressed side-wise close together, the lugs 18 forming an end stop. When all the members are in this position, the ends of the slats are in register with openings on the inside opposite surfaces of the end members 44 and 46. These openings take the form of longitudinal slots or kerfs 53 wide enough and long enough to accommodate the ends of all of the slats when the latter are assembled together.

Each of the ends of the members 44 and 46 is provided with a circular dowel pin 54. These dowel pins, when the various members are assembled together, enter corresponding circular holes in the opposed inner faces of the side legs 48 and 50. Having laid the various parts in assembling position, the parts being indicated in dotted lines in Fig. 2, the lever 24 still being in the position *a*, as shown in Fig. 3, the lever is then moved to the position *b*, and the cylinder 5 is energized and pushes forward the plunger block 12. The ends of the slats are thus forced into the corresponding slots in the end members 44 and 46. In order to prevent the breaking of the slats and to bring the dowel pins of the end member 46 into proper register with the holes in the side legs 48 and 50, the plunger block is furnished with an adjustable screw stop 55, which is adjusted to strike the edge 56 of the slot in the base casting at the proper point. This operation, besides assembling the slats, brings about the proper positioning of the end member 46 for the next step in the assembling process, which consists in moving the lever 24 from the position *b*, through the position *a*, and to the position *c*. This, as before described, results in the withdrawal of the plunger 12 by the cylinder 5 while the lever is passing through the middle position, and when the latter reaches the position *c*, the cylinder 6 is operated and the plunger 14 pushed forward. When this occurs, the dowel pins in the ends of the members 44 and 46 enter their corresponding holes in the members 48 and 50, and the assembling process is complete. Before straightening up the lever 24, it is customary to drive a small tack or nail from the upper side of each side member into and through the center of each of the dowel pins. The lever is then returned to the middle position *a*, and the chair-back removed, completely assembled.

In its broader aspects, the invention is not limited to the details of construction set forth above, except as specified in the appended claims.

I claim as my invention:

1. A panel assembling mechanism comprising a base-frame and fluid-pressure operated means working at substantially right angles in a plane parallel to the working surface of the base-frame, said working surface carrying abutments at substantially right angles to each other and having spaced parts at a higher level to support material, and stops having a wide range of adjustment between said abutments, means on said spaced parts at another level to support material of different thickness, and valve connections causing the alternate advance and retreat of the fluid-pressure means.

2. A panel assembling mechanism com-

4

prising a base-frame and fluid-pressure operated means working at substantially right angles in a plane parallel to the working surface of the base-frame, said working surface carrying abutments at substantially right angles to each other and having spaced parts at a higher level to support material, and stops having a wide range of adjustment between said abutments, means on said spaced parts at another level to support material of different thickness, a portion of an abutment adjacent a fluid-pressure means serving as a position stop therefor, and an adjustable stop carried by one of these elements engaging the other, and valve connections causing the alternate advance and retreat of the fluid-pressure means.

3. A panel assembling mechanism comprising a base-frame and fluid-pressure operated means working at substantially right

angles in a plane parallel to the working surface of the base-frame, said working surface carrying abutments at substantially right angles to each other and having spaced parts at a higher level to support material, 25 and stops having a wide range of adjustment between said abutments, means on said spaced parts at another level to support material of different thickness, an abutment having an under cut slot, and a fluid-pressure 30 plunger block having a foot playing in the enlarged part of the slot and connecting with the working surfaces through the narrower part of said slot, and valve connections causing the alternate advance and retreat of the fluid-pressure means.

WILLIAM H. PARRY.
